By CHARLES P. TRIMBLE,
S. V. M. E. RY
Attorney

UNITED STATES PATENT OFFICE.

CHARLES P. TRIMBLE, OF PITTSBURGH, PENNSYLVANIA, ASSIGNOR TO FORT PITT BEDDING COMPANY, OF PITTSBURGH, PENNSYLVANIA, A CORPORATION OF PENNSYLVANIA.

BED SPRING AND THE LIKE.

Application filed June 30, 1924. Serial No. 723,170.

This invention relates to bed springs and the like, and it comprises a single piece angle iron bed spring frame constructed to fit the standard wooden bed and advantageously 5 provided with means accommodating it to metal beds.

Wooden beds are, as a rule, made in certain definite sizes, and ordinarily the sides thereof are provided with means for the reception of slats or the like upon which the bed springs are mounted. Oftentimes the sides are provided with angle iron brackets or other supporting means for the springs or a frame upon which they are mounted.

10 Metal beds, although manufactured in standard single, three-quarter, and double sizes, are usually larger than wooden beds of the same sizes, and also the means for supporting the springs are of different construction.

It is one of the objects of the present invention to provide a single piece bed spring frame which can be used on metal as well as wood beds.

25 Another object of the invention is to provide a strong and durable frame for bed springs, which will retain its shape, and which is made of a minimum number of parts.

30 A further object is to make a bed spring frame which is sanitary, being provided with rounded corners whereby the accumulation of dust and dirt is eliminated.

Other and further objects will appear in 35 the following description taken in connection with the accompanying drawings, in which

Figure 1 is a perspective view of the spring frame, the springs being omitted for 40 simplicity of illustration.

Figure 2 is a detail sectional view taken along the line 2—2 of Figure 1, showing the manner of connecting the ends of the angle iron frame.

45 Figure 2^a is a view, similar to Figure 2, showing a modified form of connection for the ends of the angle iron frame.

Figure 3 is a view showing one method of attaching the springs to the spring frame.

50 Figure 4 is a sectional view taken along the line 4—4 of Figure 3.

Figures 5 and 6 illustrate different ways of attaching the springs to the spring frame.

Figure 7 is a top plan view showing one form of extension means. 55

Figure 8 is a side elevation of the extension means shown in Figure 7.

Figure 9 is a top plan view of a modified form of extension means.

Figure 10 is a side elevation of the modified form of extension means shown in Figure 9. 60

Figure 11 is a plan view of another modified form of extension means, and

Figure 12 is still another modification of 65 the extension means.

Referring more particularly to the drawings:

A bed spring frame 1 of angle iron formation is bent into rectangular shape, and the 70 meeting ends 2 and 3 are fastened together by means of a plate 4 and rivets 5. As an alternative construction the ends of the angle iron frame may be advantageously secured together by means of a plate 6, also of angle 75 iron construction, having portions 7 thereof crimped, or otherwise deformed, to engage similarly formed portions of the meeting ends of the frame.

The fastening of the ends 2 and 3 of the 80 frame might also be advantageously accomplished by slotting portions thereof, and deforming the metal of the fastening plate to engage in said slotted portions.

The frame 1, being of a single continuous 85 piece of metal, presents rounded corners which resist the accumulation of dust and dirt, and the frame can accordingly be kept in a clean and sanitary condition.

In order to accommodate the bed spring 90 frame to metal beds, which are often larger than those made of wood, there is provided on each side a plurality of brackets. The brackets are preferably pivoted as at 8 to the horizontal face of the angle iron frame, 95 and are bent downwardly to a position inside the frame where they may pass through slots 9 formed in the vertical face thereof so that the extremities 10, when in position, may engage the frame supporting structure 100 of the bed.

In Figures 7, 9, 11, and 12 are shown 105 different forms of brackets for this purpose. The form shown in Figure 7 consists of the bent metal arm provided with a downwardly extending flange 11. The width of the

2
bracket at its extremity, and at the flange, is preferably slightly less than the width of the hole or slot 9 so that when it is not in use it may be withdrawn completely inside 5 the spring frame, and not interfere with the use of the spring on a wooden bed. In the form shown in Figure 9 the bracket comprises three arms 12, 13, and 14, pivoted respectively at 15 and 16. This arrangement 10 permits not only a larger adjustment, but also makes possible the positioning of arm 14 substantially at a right angle to the side of the spring frame. The arm 14 is also provided with a downwardly extending 15 flange 11.

In the form shown in Figure 11, the arm 17 is provided with a longitudinal slot 18, and the arm 19 has mounted on one end thereof a stud 20 which is adapted to ride 20 in the slot 18. This construction permits of additional adjustment longitudinally of the frame, the slots 9 being lengthened accordingly. In Figure 12, the arm 21 has a single arm 22 pivoted thereto as at 23, and 25 in this instance the slot 9 in the vertical face of the frame is lengthened to accommodate the arm 22 at different angles.

It is to be understood that the spring frame is provided with cross bars which 30 serve to support springs in the usual manner. The outside springs may, however, be directly attached to the horizontal face of the angle iron frame in a number of different ways. As shown in Figure 3 the lower- 35 most convolution 24 of the spring overlaps the upper face of the frame, and the spring is held in position on the frame by a clip 25, passing inside the frame, and bent over the lower edge of the vertical portion there- 40 of, as at 26. In Figure 5, the vertical face of the frame is notched at 27 for the recep- 45 tion of the clip 25, while in Figure 6 the vertical face of the frame is provided with a hole 28 for the reception of the bent end 29 of clip 25.

Having now described my invention, what I claim is:—

1. In a spring construction, an angle frame, means pivoted upon one face of said frame and extending through the other face thereof, whereby said means can be swung exteriorly of said frame for adapting it to different sizes of beds and can be swung interiorly of the periphery of said frame when not in use. 50

2. In a spring construction, a continuous frame of angle iron construction having horizontal and vertical faces; a plurality of slots formed at intervals in the vertical face of said frame; bracket members pivoted to said horizontal face, and adapted to be swung through said slots and to extend exteriorly of said frame whereby said frame 55 may be adapted for use on different sizes of beds. 60

3. In a bed spring construction, a frame of angle iron form, having horizontal and vertical faces; a plurality of slots formed in the vertical face of the frame; a plurality of brackets pivoted to the horizontal face of 70 said frame, the said brackets extending inwardly of the frame and downwardly into the plane of said slots whereby said brackets may be projected through said slots to extend beyond the external limits of said 75 frame. 75

4. In a spring construction an angle iron frame, brackets pivoted on the horizontal surface of said frame and adapted to swing through slots in the vertical surface thereof 80 to project exteriorly of said frame and to swing interiorly of the periphery of said frame when not in use, and downward-turned lips formed integrally with the ends of said brackets for engaging the frame of 85 a bed. 85

In testimony whereof, I have hereunto affixed my signature.

CHARLES P. TRIMBLE.
